DETACHABLE SHOE CLEAT

Melvin A. Robinson, Washington, D. C.

Application October 15, 1946, Serial No. 703,385

3 Claims. (Cl. 36—7.7)

1

The present invention is a ground gripping device or cleat designed as a temporary attachment to the soles of the wearer's shoes, with the purpose of affording to the wearer a sure footing when engaged in such athletics as golf and hiking or the like.

One advantage of this device, readily attachable to, and equally readily detachable from any shoe, is that it may be employed without marring the appearance or damaging the construction or materials of the shoe.

Another advantage of this invention rests in the fact that, despite its simple construction, its positive grip mechanism is of such a nature that once adjusted and clamped to the shoe the possibility of its coming loose and detaching itself therefrom, as a result of the stresses and strains imparted to it during its normal use, are nil.

A further advantage is that the adjustability of this device is such that a proper fit may be obtained for a large range of sizes of adult shoes common to the market.

The construction of this device consists, in general, of three elongated strips of metal, or other suitable material, so arranged and attached to one another as to enable it to be attached to the bottom side of the sole of a shoe and to be there clamped and held in position; and further, said strips are so arranged as to impart to the device a degree of expansibility enabling it to fit various sized shoes. Two of these strips are substantially equal in length and design and are arranged so as to cross each other at approximately two fifths of their length from one end of each of these strips and are there pivotally attached to each other, thus producing one pair of longer arms and one pair of shorter arms. Extending across the two longer arms is the third mentioned strip, pivotally secured to one of these arms at one end while containing an elongated slot at its other end whereby it is slidably attached to the other arm.

At each end of each of the first two mentioned strips, a portion of said strip is turned up and back in such a manner as to enable said portion to firmly grip and hold to the periphery of the sole. Depending from the bottom faces of these strips are several substantially pointed calks or spikes whereby the additional traction between the wearer and the ground is attained.

One phase of the present invention resides in the employment of the shanks of some of the pointed calks or spikes for pivotally securing the strips, where relative pivotal movement of the elements of the cleat is had; and the employ-

2

ment of at least one pointed calk or spike as a means for securing the several elements in adjusted position. Thus some of the calks, in addition to serving their normal function as ground grippers, also serve as securing devices, some serving to secure the strips together in pivotal relation and at least one being provided with a threaded shank and cooperating with a threaded nut to fix the entire device in its adjusted position.

The pivotal construction, at the intersection of the two substantially similar strips, working in conjunction with the elongated slot construction of the third mentioned strip, supplies the means for adjusting the device to different sized shoes, as it affords to those arms intended to grip the sole of the shoe a greater or lesser transverse span across the shoe's bottom. Once positioned on the shoe, the movement of any arm or strip with relation to any other parts of the device is prevented by tightening the threaded calk and lock washer arrangement upon the sides of the above mentioned elongated slot; while its removal is accomplished by loosening this arrangement, thus affording each section its original relative freedom and enabling the device to be disengaged from the shoe. In addition, this anti-skid device is designed with a slight outward curvature from its inner face in order to better enable it to fit the contour of a shoe's bottom.

A fuller and more detailed description of this device is given below in conjunction with the accompanying drawings, forming a part of this specification, and in which:

Figure 1 is a bottom face view of a shoe with the cleat or anti-slipping device attached thereto.

Figure 2 is a side view of a shoe with the cleat attached thereto.

Figure 3 is a cross section view of the calk, nut, and lock washer arrangement taken along the line 3—3 of Figure 1.

Figure 4 is a cross section view of a depending calk or spike fixedly attached to and riveted on one of the strips and is taken on line 4—4 of Figure 1.

Figure 5 is a top face view of the nut used in the adjusting arrangement.

Figure 6 is a face view of the lock washer used in the bolt, nut and lock washer mechanism.

The same reference characters represent the same parts when they appear in more than one figure.

Nos. 10 and 20 represent two crossed elongated strips, pivotally mounted on one another by means of the calk 11. The intersection of these two

strips at 11 is so positioned on each as to make the shorter portion approximately two-fifths the length of the entire strip. With the shorter portion reaching to the inside edge of the shoe and the longer over to the outside edge, a more perfect fit and more firm grip are attained when the device is adjusted to various sized shoes than if the intersection at 11 were centrally located along the two strips 10 and 20. The longer arms of the strips 10 and 20 provide a greater spread along the more gently curved and more nearly straight, and longer outside edge of the sole; while the shorter arms of the strips 10 and 20 provide a relatively short spread for engaging the more curved inside edge of the sole.

The calks 12, employed in the present invention, are shaped as shown in Figure 4 and include a base plate, a pointed ground gripping spike portion extending from one side of the base plate and a shank portion.

Calk 14 is secured to strips 10 and 20 and holds the two strips in pivotal engagement, the shank of the calk being swaged or peened for the purpose; although not specifically illustrated, it is identical in construction to calk 12 illustrated in cross section in Figure 4, showing the extending rivet 13. Calk 15 likewise holds strips 14 and 20 in pivotal engagement.

Figure 2 is a side view of the cleat attached to sole 16 of shoe 17. In particular, this figure illustrates the turned up and over portions 18 of strips 10 and 20 designed to securely grip the edge of the sole 16. In addition, Figure 1 shows at 19 that portions 18 are bent on a diagonal line across strips 10 and 20 rather than on a right angle line in order that portions 18 might more nearly fit the contour of the shoe's sole.

Strip 14 is pivotally attached to 20 by calk 15 and extends beyond calk 30 located on strip 10. The shank portion 32 of calk 30 passes through elongated slot 40 and through strip 10.

The means whereby the various portions of the cleat or anti-slipping device may be held in position with relation to one another, is located at and is in part integral with calk 30. Figure 3 is a cross section view of this fastening mechanism and shows the calk 30, its threaded shank 32, the lock washer 31, and nut 33 in their positions relative to one another. The nut 33 has upturned serrations 34 which pass through suitable openings in strip 10 and are bent over on the opposite face of the strip, thus insuring said nut against rotation when shank 32 is turned by applying a spanner wrench to holes 35 in calk 30 and turning same for the purpose of either loosening or tightening this clamping mechanism.

The nut 33 has an interiorly threaded shank 51 which passes through the opening in the strip 10, through the sole 40 in connection or adjusting strip 14, and is swaged or peened over to form shoulders 52 which engage the edges of the slot 40, thereby serving to hold the strips 10 and 14 in permanent assembly and providing a guide for the sliding movement of strip 14 on strip 10. The lock washer 31 rests on the strip 14 and is interposed between it and the plate like enlarged portion 53 of the calk 30.

Thus, with the clamping mechanism loosened, the cleat is fitted snugly to the sole of the shoe and the clamping mechanism is tightened by turning calk 30 by means of a spanner wrench. Once secured, this mechanism will not loosen in the normal use of the device because of the action of the lock washer 31. To remove the cleat from the shoe, calk 30 is turned by use of the

spanner wrench again so as to loosen the clamping mechanism thus restoring to each part its pivotal freedom and enabling the cleat to undergo a transverse expansion, thus removing it from the shoe.

The drawings and the above specification disclose one form of the invention. It will be understood, however, that the present invention is not limited thereby, and variations thereof embodying the principles of the present invention will be apparent to persons skilled in the art. Thus as one variation the strip 14 may be integral with the strip 20 and the slot 40 would then be curved to provide for the arcuate movement of the calk 30. In all forms of the invention a calk is employed for the adjustment of the cleat to the shoe and for fixing the cleat in adjusted position; and in all forms the main element, namely the strips 10 and 20, or what may correspond to these strips, are pivoted at a point so as to provide a pair of long and a pair of short arms for maximum range of adjustability.

I claim:

1. A detachable shoe cleat comprising a pair of swingably connected elements having integral sole gripping clips, one of said elements having an opening spaced from the point of swingable connection, the other element having a part provided with an elongated slot overlying said opening, and means for holding said elements in adjusted position comprising a threaded socket passing through said opening and slot, the socket having at one end an integral disc engaging the outer face of the first mentioned element, the disc having upstruck portions passing through the element, and a calk having a threaded shank entering said socket and having an integral disc-like enlargement for fixing the elements in adjusted position.

2. A detachable shoe cleat comprising a pair of pivotally connected elements, each of said elements having turned up ends to grip the edge of the sole of a shoe, a strip connected at one end to one of said elements and slidably connected at the other end to the other of said elements, calks carried by said elements, one of said calks serving to hold the pair of elements in pivotal relationship, said strip having an elongated slot, one of said elements having an opening, a threaded socket passing through said opening and slot, the socket having at one end an integral disc engaging the outer face of the last mentioned element, the disc having upstruck portions passing through the arm, the socket having at its other end a shoulder engaging the strip, and a calk having a threaded shank entering said socket and having an integral disc-like enlargement for fixing the elements in adjusted position.

3. A detachable shoe cleat comprising a pair of strips, a bar pivotally mounted on one of said strips and slidably mounted on the other of said strips, calks carried by said strips, one of said calks serving to hold the pair of strips in pivotal relationship, another calk serving to hold the bar and one of said strips in a pivotal relationship, said bar having an elongated slot, the other of said strips having an opening, a threaded socket passing through said opening and slot, the socket having at one end an integral disc engaging the outer face of one strip, the disc having upstruck portions passing through the strip, the socket having at its other end a shoulder engaging the bar, and a calk having a threaded shank entering said socket and having an integral disc-like

enlargement for fixing the elements in adjusted position.
